WILLIAM J. FALLON, JR., OF BOSTON, MASSACHUSETTS

WELTING

Application filed March 5, 1929. Serial No. 344,323.

This invention relates to improvements in
welting of increased thickness, and method
of making the same.

In manufacturing boots and shoes it is
sometimes desirable to employ welting having
a greater thickness than the leather stock
from which the welting is cut.

This welting of increased thickness gives
the shoe in which it is used the appearance
of having a thick outsole or of having the
weight and wearing properties of the shoe
otherwise increased, but if the increased
thickness of the welting is imparted to the
welt strip throughout its width the inner
edge portion of the welting will be too thick
to fit snugly in the crease of the shoe.

It has therefore been the general practice heretofore in employing welting of increased thickness to form the same of two
20 welt strips secured one on top of the other, each being rectangular in cross-section throughout the greater portion of its width but having the stock partly cut away near its inner edge to facilitate the insertion of
25 the double welt strip in the crease of the shoe.

This method of forming welting of increased thickness however is open to the objection that it requires twice the amount of
30 stock as the ordinary welting, and furthermore, when the usual groove for the inseam stitches is formed in that portion of the welting which has been partly cut away to decrease its width, the remaining portion of the stock at this point may not be thick enough to afford the strength required to withstand the strain of the inseam stitches.

The present invention therefore contemplates a construction whereby a substantial saving in welt stock is secured in producing thick welting, and at the same time ample stock is provided to receive the groove for the inseam stitches and to prevent the stitches from tearing through the stock at this point.

The various features of the invention and method of carrying out the same will be best understood from the following description when read in connection with the drawings:—

50 In the drawings:—

Fig. 1 is a perspective view of a strip of
welting;

Fig. 2 is a perspective view showing the
welting of Fig. 1 split by a diagonal cut to
form two wedge-shaped strips; 55

Fig. 3 is a perspective view showing three
wedge-shaped strips disposed in spaced relation
to each other;

Fig. 4 shows the strips of Fig. 3 assembled
to form a strip of thick welting; and 60

Fig. 5 is a transverse sectional view through
a portion of a shoe provided with the welting
of Fig. 4.

In carrying out the present invention the
strips of stock employed in forming the thick
welting of Fig. 4 may be secured from any
suitable source of supply, but these strips are
conveniently obtained from strips of welting
10 such as shown in Fig. 1. The strip of
welting 10 is split diagonally by a cut 11 70
formed at an acute angle to a face of the welting
to produce the strips 12 and 13 that are
wedge-shaped in cross-section. 75

All of the wedge-shaped strips in Fig. 3
may be produced by splitting two welt strips 75
10 as shown in Fig. 2, in which case four
wedge-shaped strips will be provided, only
three of which will be required to form the
thick welting of Fig. 4. However, any one
or more of the strips of Fig. 3 may be pro- 80
duced through other expedients than that of
splitting a welt strip 10 diagonally.

Having obtained the three wedge-shaped
strips shown in Fig. 3, they are arranged so
that two of these strips, for example, 12 and 85
13, have their thick portions disposed at the
outer edge of the finished welting, while the
third strip 14 is inserted between the other
two strips with its thick portion disposed at
the inner edge of the finished welting, as will 90
be apparent from Fig. 4.

The upper face of the upper strip 12 should
constitute the grain face of the leather, the
other strips 13 and 14 need not have a grain
face. 95

It will be apparent from the construction
just described that the thick welting of Fig.
4 can be produced from three of the four
wedge-shaped strips obtained by splitting two
strips 10 diagonally, thereby securing a sav- 100

ing of 25% in stock over the thick welting above described as employed heretofore. Furthermore, as a result of the present construction the thick portion of the strip 14 disposed at the inner edge of the finished 5 welting provide sufficient stock adjacent the stitch receiving groove 15 to withstand the strain of the inseam stitches 16 employed to bind the welting and shoe upper 17 to the inner sole 18.

10 It is important that the feather edge 19 of the upper strip 12 be prevented from working loose from the filler strip 14, and this is accomplished, in accordance with the present 15 invention, by providing the filler strip 14 with the bevel 20 to which the lip 19 is secured. As a result the thick filler strip is given a beveled face that causes it to fit snugly 20 against the shoe upper 17 and the lip 19 is directed downwardly along the upper in position 25 to be further secured in place by the inseam stitches 16. The parts of the thick welting are further secured together by the outsole stitches 21 provided to secure the outsole 22 to the welting.

25 What is claimed is:—

1. As an article of manufacture, a strip of 30 welting of increased thickness formed of three strips of stock each wedge-shaped in cross-section and secured together one on top of the other with the thick portion of one wedge-shaped strip lying between the thin portions of the other two wedge-shaped strips.

2. As an article of manufacture, a strip of 35 welting of increased thickness formed of three strips of stock each wedge-shaped in cross-section and secured together one on top of the other with the thick portion of one strip lying between the thin portion of the other two strips and the upper strip having 40 its thin edge portion secured to a bevel formed upon the thick portion of the intermediate strip.

3. As an article of manufacture, a strip of 45 welting of increased thickness and formed of a portion that is substantially rectangular in cross-section and of a portion secured thereto that is wedge-shaped in cross-section the latter having its thin part positioned to lie in the crease of a shoe and its thick part positioned to lie flush with the outer vertical edge 50 of the welting.

4. As an article of manufacture, a strip of 55 welting of increased thickness and formed of a portion that is substantially rectangular in cross-section but has a beveled edge and of a portion secured thereto that is wedge-shaped in cross-section, the latter having its thin part secured to the bevel of the first 60 mentioned portion and its thick part positioned to lie flush with the outer edge of the welting.

5. As an article of manufacture, a strip of 65 welting formed of two pieces of welt stock each wedge-shaped in cross-section and se-

cured together to form a composite welt that is approximately rectangular in cross-section, one wedge-shaped strip having its thick portion beveled, and the other wedge-shaped strip having its thin edge extending over and secured to the bevel of the other strip.

70 In testimony whereof, I have signed my name to this specification.
